PAGE 2

Fig. 3.

Fig. 4.

Fig. 5.

Fig. 6.

Fig. 7.

Fig. 1 is a perspective view of a wall hung water closet embodying my new design.

Fig. 2 is an elevational view of the front thereof.

Fig. 3 is an elevational view of the rear thereof.

Fig. 4 is a side elevational view thereof, viewed from the left hand side of the water closet as shown in Fig. 2.

Fig. 5 is a side elevational view thereof, viewed from the right hand side of the water closet as shown in Fig. 2.

Fig. 6 is a top plan view thereof.

Fig. 7 is a bottom plan view thereof.

I claim:

The ornamental design for a wall hung water closet, substantially as shown.
